TOOL HANDLE

John F. Windsor, Fairfield, Conn., assignor to The Bridgeport Hardware Manufacturing Corporation, Bridgeport, Conn., a corporation of Connecticut

Application January 21, 1937, Serial No. 121,397

1 Claim. (Cl. 279—96)

This invention relates to handles for tools, such for example as screw drivers, chisels and the like, and has for an object to provide an improved handle of simple construction in which the force of blows of a hammer or mallet on the end of the handle is transferred directly to the shank of the tool by an end member which is of practically indestructible material, and because the force of the blows is transmitted directly to the shank independently of the main or body portion of the handle, this latter portion may be made of a different material which is less expensive and which need not be of indestructible material or material capable of withstanding the force of the blows.

With the foregoing and other objects in view I have devised a construction illustrated in the accompanying drawing forming a part of the specification, it however, being understood that I am not limited to the exact details of construction shown but may use variations within the scope of the invention.

In this drawing:

Fig. 1 is an elevation of a tool embodying my invention;

Fig. 2 is a longitudinal section through the handle showing the tool and shank in elevation;

Fig. 3 is a transverse section thereof substantially on the line 3—3 of Fig. 2;

Fig. 4 is an enlarged sectional view of the upper end of the handle with the upper end of the shank shown in elevation; and

Fig. 5 is a section through the members of the handle in separated relation before being assembled, the shank of the tool being shown in elevation.

The tool illustrated is a screw driver, but this is used merely for the purposes of illustration as it will be understood the tool may be a chisel, or any other tool for which such a handle is adapted.

The tool shown comprises a screw driver bit 10 having a shank 11 which is extended through the body portion 12 of the handle. As shown the upper end of this shank projects a short distance above the upper end of the body 12, but this may be varied so long as the construction is such that the force of blows on the end of the completed handle are transmitted directly to the shank. This body 12 may be of any suitable material, preferably of some material which is of relatively low cost, such for example as wood or vulcanized hard rubber or rubber composition, to reduce the cost of the handle. These materials are satisfactory for this body member because, as will later be shown, this member is not required to

withstand the blows of a hammer or mallet on the end of the handle. The lower end of this body is ordinarily reduced as shown at 13 and enclosed in a hollow ferrule 14 which may be secured to the shank by a transverse pin or rivet 15, thus holding the body member 12 in proper position on the shank.

Secured to the upper end of the shank of the member 12 is an enlarged abutment or head member 16, preferably of a block of metal, which is drilled at 17 to receive the end 18 of the shank. At the inner end of the drilled opening 17 there is preferably a portion 19 of smaller diameter, and before applying this head to the shank the end of the shank may be tapered somewhat as 15 shown at 20. The side walls of the shank are also preferably scored or slightly grooved as shown at 21. When applying this block or abutment member to the shank the shank is of relatively tight fit in the opening 17, and by driving the block down onto the head of the shank the reduced portion 19 and the end of the shank are deformed and sort of flow or run together so that the block 16 is in effect in one piece with the shank with no danger of working loose. The 25 metal of the block more or less runs into the scoring 21 in the shank and helps to secure the two together, and it also helps prevent relative turning between them.

The drawing in Fig. 4 shows the end of the shank deformed into the reduced portion 19, but this is merely for illustration only as it appears that the metal of both the head member and the shank is deformed, because the metal as indicated above appears to run together. In the 35 present showing the upper end of the body 12 is recessed at 22 to receive the lower end of the head members 16, but this is not necessary, it being used in the present case to permit the use of a longer member 16 with a shallower recess in 40 the cap or end member 23.

This member 23, as will be evident because of its location, must receive directly the force of a hammer or mallet blow on the end of the handle. It must therefore be of some material which 45 is resistant to breaking or deformation under these blows to a high degree. I have found a material which is known on the market as "Pyralin" to be very satisfactory. This is a cellulose nitrate material which I have found to be very well 50 adapted for this purpose as it is practically indestructible, may be easily applied, and is a good electrical insulator so that if the body portion 12 of the handle is also of insulating material the whole handle is insulated. This cap 23 is formed 55

with a recess 24 to receive the abutment or head member 16. This material has the property of softening somewhat when at the proper temperature, and if the recess 24 is somewhat smaller than the diameter of the block 16 the cap may be easily forced onto this block or head when this material is in the heated condition. The outer walls of the head 16 are also preferably grooved or scored or otherwise roughened as indicated at 10 25 so that when the head is forced into this softened material it flows into these recesses and after hardening the cap is rigidly secured to the head with no danger of its loosening or turning in operation.

15 The cap 23 is preferably of an outside diameter substantially equal to that of the body 12 and its lower end is in substantial engagement with the top end of the body to give a smooth handle of attractive appearance. It will, however, be seen 20 that the cap 23 is secured to the shank 11 entirely independently of the body member 12. It will also be seen that the force of any blow on the top or outer end of the cap 23 is transmitted directly to the head 16 and by it to the shank 11 inde- 25 pendently of the body member 12, and therefore this body member is not required to take any of the force of these blows. I am of course not limited to the use of cellulose nitrate or the particular cellulose nitrate mentioned, but it will be evi- 30 dent I may use any other similar material which has similar characteristics so as to be capable of

being applied to the shank in a similar manner to transmit the force of the blows directly thereto, and also if this material has the characteristics of resisting or withstanding these blows without breaking or deforming to an objectionable extent. It is probable there are synthetic resins or other similar materials which can be used for this purpose.

Having thus set forth the nature of my invention, what I claim is:

A tool of the character described comprising a handle including a non-metallic body member, a tool member having a metal shank extending longitudinally through the body member, a separate enlarged metallic head member having serrations on its outer peripheral surface, said head being rigidly secured by a forced fit to the end of the shank at the outer end of the body member, and a cap member of substantially the diameter of the body member at its outer end, said cap member being of a molded material different from those of the body and head members and such as to be highly resistant to breaking and deformation under blows of a hammer or mallet, and said cap having a recess to receive said serrated head member and to which it is rigidly connected by forced fit so that the force of the blows on the cap is received by the head member and transferred by it to the shank.

JOHN F. WINDSOR.
